UNITED STATES PATENT OFFICE.

JAMES J. LONERGAN, OF CLEVELAND, OHIO.

DESIGN FOR A CATCH-BASIN.

SPECIFICATION forming part of Design No. 29,706, dated November 22, 1898.

Application filed October 17, 1898. Serial No. 693,883. Term of patent 7 years.

To all whom it may concern:

Be it known that I, JAMES J. LONERGAN, a citizen of the United States, and a resident of Cleveland, county of Cuyahoga, State of Ohio, have invented and produced a certain new and useful Design for a Catch-Basin, of which I hereby declare the following to be a full, clear, and exact description, such as will enable others skilled in the art to which it applies to make and use the same.

Figure 1 is a plan view of the catch-basin, showing my new design. Fig. 2 is a side view thereof. Fig. 3 is a sectional view on line x - x , Fig. 1.

As shown in the drawings, the leading or material features of the invention are the depressed inner extremity 1 of the perforated top plate 2 and the overhanging lip 3 of the

exterior ring 4, oppositely placed to the depressed portion of the top.

The general shape of the design is that of a flattened cylinder 4, the top 2 being perforated with rectangular openings, the bottom being open at 6. A rim 7 is seen at the lower edge, also circular in shape.

Having described my invention, what I claim as new, and desire to secure by Letters Patent, is—

The design for a catch-basin substantially as shown and described.

Signed by me, at Cleveland, Ohio, this 8th day of October, 1898.

JAMES J. LONERGAN.
